THREAD ROLLING APPARATUS

Victor Hill Fray, Auckland, New Zealand

Application September 2, 1950, Serial No. 182,977

Claims priority, application New Zealand
October 13, 1949

8 Claims. (Cl. 80—7)

1

This invention relates to thread rolling apparatus whereby screw threads are formed by a rolling process on blanks of metal thread screws, bolts and the like, the objects of the present invention being the provision of improved thread rolling apparatus which will very appreciably speed up the forming of the rolled threads on the blanks.

While the known flat plate reciprocally operated type of thread rolling apparatus is that which is in general use, I am aware that rotary roller type thread rolling apparatus is known, but that it has not come into general use even though devised many years ago, because of not being positive and consistent enough in its action.

The present invention has been devised to provide improvements in the rotary roller type of thread rolling apparatus which will enable numbers of blanks to be progressively roll threaded in the machine at the one time, to enable positive entry of the blanks to the machine at correct intervals to accurately agree with the correct register of the thread starts of the thread roller and the threaded segment and to give what may be considered as a power feed of the blanks to the machine to enable same to be disposed horizontally as against the usual inclined position when the blanks are fed to same by gravity feed.

Broadly the invention comprises improvements in thread rolling apparatus comprising a thread rolling apparatus having a thread roller mounted on a spindle which is rotatably carried by bearings in a head, with the threaded curved face of a stationary segment disposed adjacent to said roller, a gap between said thread roller and the segment, a hopper for delivering blanks to a conveyor, feed wheel means for carrying the blanks from the conveyor directly into the gap between the thread roller and the segment, guide block means disposed around portion of the feed wheel to hold the blanks on the feed wheel while carried thereby, and a drive to the feed wheel to give it rotation which is fixed in its relationship to that of the thread roller.

In describing the invention, reference will be made to the accompanying drawings in which:

Figure 1 shows an elevation of the thread roller and hopper feed apparatus as mounted to a common bedplate,

Figure 2 is a plan view of Fig. 1, but with the bedplate deleted and not showing trays, band guards and such like which are portions of the hopper feed apparatus,

2

Figure 3 is an elevation of the thread roller apparatus.

Figure 4 is a side elevation and

Figure 5 is a plan view thereof,

Figure 6 is an enlarged plan view of the apparatus in the vicinity of the feed wheel,

Figure 7 is a sectional elevation on line A—B of Fig. 6,

Figure 8 is a partial sectional plan view taken between the upper and lower portions of the feed wheel,

Figure 9 shows a partial plan view similar to that of Fig. 6 but including an alignment wheel for use when the blanks to be roll threaded have countersunk heads and

Figure 10 is an elevation of the alignment wheel as applied to the feed wheel for use on countersunk head blanks.

In the invention, the known thread roller apparatus comprises (see Figs. 3, 4 and 5) a vertical spindle 1 with a thread roller 2 rigidly secured near the top thereof and mounted in bearings 3 and 4 which extend horizontally from the vertical portion 5a of a main frame or head 5 which is rigidly secured to a bedplate or the like 6, provision being made by gearing or the like such as a wormwheel 7 (see Fig. 1) on the bottom of the spindle 1 engaging a worm 8 on a drive shaft 9 for drive of this spindle 1 and the roller 2 thereon, portion of the periphery of the roller 2 being disposed closely adjacent to the curved face 10a (see Fig. 5) of a stationary segment 10 which is adjustably and slightly eccentrically mounted to the vertical portion 5a of the main frame or head 5 so as to leave a gap 11 between the roller 2 and the segment 10, the curved face 10a of the segment 10 being provided with the forming threads which are complementary to the forming threads in the periphery of the thread roller 2, means being provided to enter the blanks to the gap inlet or feed-in end 11a.

Hopper-feed apparatus which is substantially of the type as described in my previous U. S. A. patent application Serial No. 95,492 of May 26, 1949, now Patent No. 2,639,445 issued May 26, 1953 is also mounted to the bedplate 6 and is used in conjunction with the thread rolling apparatus for feeding the blanks to the latter at the required speed, such hopper-feed apparatus having a rotatable hopper 12, a pair of rollers 13 with a drive spindle 14, an endless conveyor belt or band 15 passing over rotatable band wheels 16 and 16a which are disposed at opposite ends of the bedplate 6 and a rigid bar 17 and rubbing strip 18 (see Fig. 6) disposed par-

allel with the band 15, a vertical gap 19 being presented between the rigid bar 17 and the said band 15 down within which the shank portions 20a of the blanks 20 hang, with their heads 20b resting on the top edge of the band 15 and, if desired, on the top edge of the rigid bar 17.

For the purposes of the present invention, drives to such hopper-feed apparatus are obtained from the drive shaft 9 (see Fig. 2) there being a pulley 21 on the drive shaft 9 connected by belt 22 to a pulley 23 on a countershaft 24, a further pulley 25 on this countershaft 24 being connected by belt 26 to a pulley 27 on a pinion shaft 28, the pinion 29 on the latter being in mesh with a gear ring 30 which is secured to the back of the hopper 12.

The countershaft 24 also transmits a drive as through skew gearing 31 to the drive spindle 14 of the pair of rollers 13, a further pulley 32 on the drive shaft 9 being connected by a belt 33 to a pulley 34 on a bevel pinion shaft 35, the bevel pinion 36 being in mesh with a bevel wheel 37 which is secured to the band wheel 16a, the drive shaft 9 itself being driven as by an electric motor 38 in a suitable manner such as the belts 39 and pulleys 40 and 41 shown in the drawings.

The conveyor means as presented by the travelling band 15 and the rigid bar 17, convey the blanks 20 toward the thread rolling apparatus, special means being provided for removing the blanks from the conveyor means and for effecting entry of same to the thread roller apparatus at correct intervals which will accurately agree with the correct register of a thread start of the thread roller 2 and the third start of the threaded segment 10.

At a point on such conveyor means where the flexible band 15 passes the thread roller apparatus, the rigid bar 17 ends (see Fig. 6) to permit of the introduction of a feed wheel 42, such feed wheel 42 being disposed on a vertical shaft 43 and having ratchet like teeth 42a at the upper and lower portions 42b and 42c thereof, with a plain reduced diameter portion 42d between these portions, the teeth 42a and the recesses or spaces between such teeth coinciding in the upper and lower portions 42b and 42c of the wheel 42, the pitch of the teeth being preferably such as to agree with the distance between each two starts of the thread rolling portion of apparatus.

The periphery of such feed wheel 42 sweeps across and blocks the space or gap 19 between the rigid bar 17 and the travelling band 15, as being just short of in contact with the latter, and it also sweeps across the feed-in gap 11a between the thread roller 2 and the stationary segment 10, it being the object of this feed wheel 42 to pick up the blanks 20 from the conveyor and to divert and carry them into the said feed-in gap 11a of the thread rolling apparatus.

The top level of the feed wheel 42 coincides with the top level of the conveyor band 15 and similarly coincides with the top level of the thread roller 2 and segment 10, but as the feed wheel 42 cuts across portion of the segment 10 at the feed-in gap 11a, said segment 10 has arcuate slots 10b cut therein to permit of free passage of the feed wheel 42 with just moderate clearance, the segment 10 presenting tongue like portions 10c which extend to between the upper and lower portions 42b and 42c and also under the lower portion 42c.

A rigid guide block 44 has an arcuate face 44a which is disposed adjacent to the side of the feed wheel 42, this block 44 extending from near the band 15 to near the thread roller 2, the rigid bar

17 also extending to near the opposite side of the feed wheel 42.

There is a positive drive between the thread roller 2 and the feed wheel 42 so that the slots or spaces between the teeth 42a of the latter will register correctly with preferably every second start of the thread roller 2, the direction of rotation of this feed wheel 42 being such as to pick up the blanks as travelling to same along the conveyor band 15 and to divert them to the thread roller apparatus which takes them off the feed wheel 42.

This positive drive between the thread roller 2 and the feed wheel 42 comprises (see Figs. 3, 4 and 5) a gear wheel 45 secured to the top of the thread roller spindle 1 above the thread roller 2, this gear wheel 45 being in mesh with an intermediate gear wheel 46 which is rotatably mounted to a bracket 47 which is secured to the head 5, this bracket 47 carrying a radially moveable arm 48 at the outer end of which a second intermediate gear 49 is rotatably mounted, the latter being in mesh with the gear wheel 46 and with the feed wheel gear 50 which is secured to the feed wheel spindle 43 at a level above the feed wheel 42, this feed wheel spindle 43 being rotatably mounted within the bearing housing portion 51a of a bracket 51 which is secured to the head 5.

It will be obvious that other positive drives could be applied between the thread roller spindle 1 and the feed wheel 42.

The apparatus described is satisfactory when handling blanks which have round heads or cheese heads, in that these present flat faces under their heads which bear flat on the band 15 and the rigid bar 17, but the blanks which have countersunk heads do not travel along the conveyor means so uniformly upright because of their angular undersides.

The result is that occasionally a blank 20 is not truly upright when it reaches the feed wheel 42 and there may be a jambing tendency because of the shanks 20a not passing fairly to between the upper and lower teeth 42a of the feed wheel 42, upper and lower portions 42b and 42c.

To overcome this difficulty which applies only in respect of the countersunk headed blanks, an alignment wheel 52 (see Figs. 9 and 10) is located just above the feed wheel 42 substantially at the position of entry of the blanks 20 to said feed wheel 42, this alignment wheel 52 having recesses 52a formed in its periphery which are such as will be suited to engage around substantially half of a countersunk head.

This alignment wheel 52 is freely rotatably disposed on an axle or the like 52b to the top of which a radial arm 53 extends horizontally to an integral or attached pair of lugs 53a, these lugs 53a being pivotally mounted on a vertical pin 54 which is held by a bracket 55 which is secured to the segment 10 or to another suitable rigid part of the head 5, a spring 56 on the pin 54 engaging between the bracket 55 and the lugs 53a to tend to force the alignment wheel 52 towards the band 15.

In use or operation, with a supply of the blanks 20 passing from the rotating hopper 12 along the travelling conveyor, these blanks 20 can travel only so far as the feed wheel 42 which blocks the gap 19 down within which the shanks 20a of the blanks 20 are hanging vertically, with the heads 20b of the blanks 20 resting on the top edges of the travelling band 15 and the rigid bar 17.

The rotation of the feed wheel 42 in causing its teeth 42a to sweep across this gap 19 of the

conveyor and as the slots or spaces between the teeth 42a are such as to take only one blank each, the blanks are caught up by their shanks 20a passing between the teeth 42a and are carried away towards the thread roller 2, their heads 20b resting on the top face of the feed wheel 42 and also on the guide block 44.

The blanks 20 while resting on the band conveyor are all separately rotating or spinning because of the band 15 travelling at a greater speed than the blanks travel along the conveyor and because of the opposite sides of the heads being supported by a rigid non-movable bar 17 and the travelling band 15, this rotation or spin of the blanks 20 being an advantage when they come into contact with the feed wheel 42 as tending to cause them to slide smoothly into the spaces between the teeth 42a of the feed wheel 42 without jamming tendency, but in the event of the sharp corner of a tooth 42a of the feed wheel 42 coming to bear hard on a blank 20, the band 15 will bend away from the feed wheel 42 to free the blank so that it correctly enters the feed wheel or drops out of the conveyor.

For this purpose there may be extra clearance between the band 15 and the rubbing strip 18 in the vicinity of the feed wheel 42, the rubbing strip terminating at the feed wheel 42, if so desired, this however not being essential.

The rotation of the feed wheel 42 is therefore resulting in the blanks 20 being carried by same from the conveyor to the feed-in gap 11 (from its end 11a) between the thread roller 2 and the threaded segment 10 and at the instant when a start of the thread roller 2 is in correct registry with the thread formation at the leading end of the stationary segment 10, the rotation of the feed wheel 42 carrying the blanks in turn into the gap 11 at which they become engaged between the roller 2 and the segment 10 to commence their rolling passage through the gap 11 to thereby have the threads applied thereto, the tongue like portions 10c of the segment 10 guiding the shanks 20a of the blanks 20 into the feed-in end 11a of the gap 11 from the feed wheel 42.

The peripheral speed of the feed wheel 42 is such as to be the speed of the travel of the blanks in passing along the curved path presented by the gap 11, this speed, due to the rolling action of the blanks, being almost exactly half of the peripheral speed of the thread roller 2.

When the blanks 20 to be roll threaded are of countersunk head type as shown in Figs. 9 and 10, the alignment wheel mechanism is applied to the thread roller apparatus and as the spring 56 is yieldingly forcing the alignment wheel 52 towards the travelling band 15, the blanks 20 encounter this alignment wheel with their heads 20b just as their shanks 20a are approaching the feed wheel 42.

Portions of the heads 20b of the blanks 20 are therefore caused to pass into the recess 52a of the alignment wheel 52, this causing them to assume upright positions if not already upright and thus their shanks 20a are truly engaged by the feed wheel 42, the rotation of the alignment wheel 52 as caused by the push of the blanks as caused by the travel of the band 15, spacing the blanks apart at the correct intervals for true entry to the feed wheel 42.

I claim:

1. A thread rolling apparatus comprising a frame, a cylindrical roller die having a continuous thread formation about its circumference comprising a plurality of thread starts, means for

rotatably supporting said roller die in said frame, a stationary die provided with an arcuate concave face having a thread formation thereon for cooperation with the thread formation of said roller die, means for fixedly connecting said stationary die to said frame with said arcuate face disposed adjacent to said roller die with a gap therebetween through which blanks to be threaded pass, power means for continuously rotating said roller die, a rotatable wheel-like member having a plurality of axially extending blank-receiving recesses about its periphery, means for rotatably supporting said wheel-like member with its periphery adjacent to the periphery of said roller die near the entry end of said gap between said roller die and said stationary die, means for continuously rotating said wheel-like member in constant relationship to the rotation of said roller die and at a peripheral speed approximately one-half of the peripheral speed of said roller die for carrying blanks positioned in said axial recesses directly into said gap between said roller die and said stationary die at an instant when a thread start on said roller die is in correct registry with the thread formation at the leading end of said stationary die, means adjacent to the periphery of said wheel-like member at a location spaced circumferentially thereabout from the entrance end of said gap between said roller die and said stationary die for automatically loading headed blanks into said axial recesses in said wheel-like member, and means disposed around portions of said wheel-like member between said last-named means and said roller die for retaining blanks in said recesses.

2. A thread rolling apparatus comprising a frame, a cylindrical roller die having a continuous thread formation about its circumference comprising a plurality of thread starts, means for rotatably supporting said roller die in said frame, a stationary die including an arcuate concave face having a thread formation thereon for cooperation with the thread formation of said roller die, means for fixedly connecting said stationary die to said frame with said arcuate face disposed adjacent to said roller die with a gap therebetween through which blanks to be threaded pass, power means for continuously rotating said roller die, a rotatable wheel-like member having spaced axial recesses about its periphery for receiving blanks the trailing sides of which are evenly spaced circumferentially with respect to each other, means for rotatably supporting said wheel-like member with its periphery adjacent to the periphery of said roller die near the entry end of said gap between said roller die and said stationary die, means for continuously rotating said wheel-like member in constant relationship to the rotation of said roller die and at a peripheral speed approximately one-half of the peripheral speed of said roller die for carrying blanks positioned in said axial recesses directly into said gap between said roller die and said stationary die at an instant when a thread start on said roller die is in correct registry with the thread formation at the leading end of the stationary die, a power-driven flat band having a portion of one reach thereof adjacent to the periphery of said wheel-like member at a location spaced circumferentially thereabout from the entrance end of said gap between said roller die and said stationary die and disposed generally parallel with the axis of rotation of said wheel-like member, a member having a surface substantially parallel with said 75 reach of said band and spaced therefrom a dis-

distance greater than the diameter of the shanks of the blanks and less than the diameter of the heads of the blanks and forming with said reach of said band a groove terminating adjacent to the periphery of said wheel-like member, means for moving said band to cause said reach thereof to move toward said wheel-like member, and means disposed around that portion of said wheel-like member between said band and said roller die for retaining blanks in said recesses in said wheel-like member.

3. A thread rolling apparatus comprising a frame, a cylindrical roller die having a continuous thread formation about its circumference comprising a plurality of thread starts, means for rotatably supporting said roller die in said frame, a stationary die including an arcuate concave face having a thread formation thereon for co-operation with the thread formation of said roller die, means for fixedly connecting said stationary die to said frame with said arcuate face disposed adjacent to said roller die with a gap therebetween through which blanks to be threaded pass, power means for continuously rotating said roller die, a rotatable wheel-like member having spaced axial recesses about its periphery for receiving blanks the trailing sides of which are evenly spaced circumferentially with respect to each other, means for rotatably supporting said wheel-like member with its periphery adjacent to the periphery of said roller die near the entry end of said gap between said roller die and said stationary die, means for continuously rotating said wheel-like member in constant relationship to the rotation of said roller die and at a peripheral speed approximately one-half of the peripheral speed of said roller die for carrying blanks positioned in said axial recesses directly into said gap between said roller die and said stationary die at an instant when a thread start on said roller die is in correct registry with the thread formation at the leading end of the stationary die, a power-driven flat band having a portion of one reach thereof adjacent to the periphery of said wheel-like member at a location spaced circumferentially thereabout from the entrance end of said gap between said roller die and said stationary die and disposed generally parallel with the axis of rotation of said wheel-like member, a member having a surface substantially parallel with said reach of said band and spaced therefrom a distance greater than the diameter of the shanks of the blanks and less than the diameter of the heads of the blanks and forming with said reach of said band a groove terminating adjacent to the periphery of said wheel-like member, means for moving said band to cause said reach thereof to move toward said wheel-like member, guide means disposed around that portion of said wheel-like member between said band and said roller die for retaining blanks in said recesses in said wheel-like member, a disk-like member disposed just above said wheel-like member adjacent to the end of said groove, said disk-like member having circumferentially spaced axially extending slots in its periphery adapted

5 to receive the shanks of blanks with their heads supported thereby, a spindle or axle for rotatably supporting said disk-like member, means for supporting said spindle or axle for movement generally perpendicular to the plane of said reach of said band, and means for urging said disk-like member in a direction to engage the periphery thereof underneath the heads of blanks in said groove.

10 4. A thread rolling apparatus as claimed in claim 1 and comprising means located adjacent to the said wheel-like member and the entrance end of the said gap for ejecting blanks from said wheel-like member and causing them to enter the gap between the said roller die and the said stationary die.

15 5. A thread rolling apparatus as claimed in claim 1 wherein the said wheel-like member comprises a wheel having upper and lower portions provided with aligned ratchet-like teeth in their peripheries and a plane reduced diameter portion between said upper and lower portion.

20 6. A thread rolling apparatus as claimed in claim 1 wherein the said means for retaining the blanks in the said slots of the said wheel-like member while carried thereby comprises a rigid guide block having an arcuate face disposed adjacent to the wheel-like member.

25 7. A thread rolling apparatus as claimed in claim 1 wherein the said wheel-like member comprises a wheel having upper and lower portions provided with aligned ratchet-like teeth in their peripheries and a plane reduced diameter portion between said upper and lower portion and wherein the said stationary die has slots cut therein at the entrance end of the gap between the said thread roller and said stationary die into which slots the upper and lower portions of the wheel-like member projects and which slots form a tongue-like portion on said stationary die extending between the upper and lower portions of said wheel-like member to eject blanks from said wheel-like member and cause them to move into said gap incident to rotation of said wheel-like member.

30 45 8. A thread rolling apparatus as claimed in claim 3 wherein the said disk-like member disposed above the said wheel-like member has semi-circular recesses of countersunk head shape formed in its periphery and wherein the said spindle or axle is supported by a radial arm extending from said axle to lugs pivotally mounted on a vertical pin secured in a bracket mounted on the said frame of the machine, and wherein a spring tends to move the radial arm and the wheel at the end thereof toward the power-driven band.
